BOBBY PIN DISPENSER

Fairfax Heiskell Gouverneur, Los Angeles, Calif.

Application November 4, 1948, Serial No. 58,180

14 Claims. (Cl. 132—1)

1

This invention relates to a dispenser for bobby pins.

Heretofore, to facilitate the use of both bobby pins and hairpins by individuals as well as beauty operators, it has been proposed to provide dispensers by which such pins will be made available one at a time, as required. For hairpins the problems has been relatively simple, requiring mainly means for preventing jamming in the dispenser. However, unlike hairpins, the ends of a bobby pin are normally pressed together and must be opened before use. To avoid the damaging effects of opening bobby pins by teeth or fingernails, a bobby pin dispenser thus must possess the additional capability of presenting the pins to the user in open or spread condition.

It is the primary object of this invention to provide an improved bobby pin dispenser having means for dispensing the pins one at a time in spread condition.

Another object of the invention is to provide an improved bobby pin dispenser for dispensing spread pins from a stack, including means for preventing jamming of the pins.

An additional object of the invention is to provide an improved bobby pin dispenser for dispensing spread pins wherein means are provided for preventing jamming between pins either while stacked or during dispensing, and for individually ejecting the pins laterally of the stack with their spread ends foremost.

A further object of the invention is to provide an improved bobby pin dispenser of relatively simple and inexpensive construction for effectively dispensing bobby pins individually in spread condition.

Other objects and advantages of the invention will appear hereinafter in the detailed description, be particularly pointed out in the appended claims, and illustrated in the accompanying drawings, in which:

Figure 1 is a plan view of a preferred embodiment of the invention.

Figure 2 is a vertical sectional view taken along the lines 2—2 of Figure 1.

Figure 3 is a vertical sectional view taken along the lines 3—3 of Figure 1.

Figure 4 is a fragmentary view of the dispensing portion of the dispenser with portions broken away to more clearly illustrate certain of the details of construction.

Figure 5 is a side elevational view taken along the lines 5—5 of Figure 1.

Figure 6 is a vertical sectional view taken along the lines 6—6 of Figure 1.

2

Figure 7 is a plan view of a second embodiment of the invention.

Figure 8 is a vertical sectional view taken along the lines 8—8 of Figure 7.

5 Figure 9 is a view similar to Figure 8, with portions removed, showing a bobby pin in process of ejection.

Figure 10 is a vertical sectional view taken along the lines 10—10 of Figure 7.

10 Figure 11 is a fragmentary side elevational view taken along lines 11—11 of Figure 7.

Figure 12 is a fragmentary vertical sectional view taken along the lines 12—12 of Figure 7; and

15 Figure 13 is a fragmentary vertical sectional view taken along the lines 13—13 of Figure 10.

Referring now in detail to the drawings, illustrating preferred embodiments of the invention and in which like reference characters designate like parts, it is contemplated that the dispenser

20 of the present invention in production form will be fabricated of plastic or other suitable material and provided with a cover hingedly or otherwise attached, by which its working mechanism will be concealed and protected. However, for purposes of illustration, the dispenser has been shown without a cover and with its mechanism for the most part exposed.

25 Referring first to Figures 1 through 6, the embodiment there illustrated is comprised of a base or case 1 for housing, receiving or enclosing a plurality of stacked or superposed bobby pins, indicated diagrammatically at 2, the case having ends 1^a and sides 1^b. Attached to or formed in the base and preferably extending along the longitudinal axis thereof is a guideway or channel 3 in which the stack of bobby pins is adapted to be seated. This guideway may be defined or delimited by parallelly disposed side or guide bars 4 and 5, one positioned adjacent each side of the case, the spacing therebetween being substantially the height or length of the usual or other bobby pin for which the dispenser is designed. As shown, the guide bars or rails 4 and 5 are adapted to guide, confront, or substantially abut, respectively, the closed and open ends of the bobby pin and confine or retain the latter therebetween.

30 To maintain or hold the bobby pins within the guide bars 4 and 5 and prevent their displacement outwardly or vertically or the guide channel 3 with consequent jamming or overlapping, it is necessary to provide means for holding the pins within the channel. For this purpose there is provided a guide member or finger 6, disposed inwardly of and substantially parallel to the guide bar 4, which finger is adapted to be threaded or

project through the closed ends of the pins. While this finger may form part of the aforementioned cover, or be fixedly or hingedly attached to the base, it has been shown removably attached adjacent the inner or lower, hereinafter to be termed the "feed" end, of the case. While the finger may be either flexible or rigid, depending on the mode of attachment, to facilitate loading of the dispenser, the disclosed removably attached finger is preferably rigid. At the other edge of the guide channel defined by the guide bar 5 the open ends of the pins are held against displacement by a hold-down plate 7 overlying the bar 5 and extending inside the bar over the adjacent edge of the guideway. As in the case of the hold-down finger 6, the hold-down plate 7 may be attached to the aforementioned cover, but is shown removably attached to the base through the guide bar 5. To facilitate contact with the confronting ends of the pins and prevent excessive wear, the plate may have an undersurface downslanting towards its inner edge to provide a detent or tip 8 capable of surface contact with the confronting faces of the pins.

It is contemplated that the bobby pins will be fed upwardly or outwardly of the feed end of the case and be discharged or dispensed adjacent the opposite end thereof. For this purpose there is provided a follower or pressure block or bar 9 which is adapted to act or bear against the under or inner side of the stack of pins. The follower block is shown as a substantially flat bar of rectangular cross-section which extends transversely of the guideway and has one or its inner end abutting against and slidably engaging the confronting face of the inner guide rail 4. Outwardly of this end the follower is transversely slotted to provide a recess or groove 10 conforming substantially to and adapted to accommodate the finger 6. So formed, the inner end portion of the follower is substantially L-shaped and adapted to slide along a track formed by the meeting walls of the inner side and bed 11 of the guideway, being retained or locked in its position transversely or laterally of the guideway and maintained against misalignment therewith through the finger 6. In the illustrated embodiment the follower extends across the guideway and is guided at its other or outer end through a transverse groove 12 formed in its outer end which is adapted to receive and slidably engage a corresponding lip or projection 13 formed in or attached to the case 1. To avoid interference with the open ends of the pins this projection extends or is disposed below the level of the bed 11 of the guide channel and extends into a recess 14 formed in the base 1 below and intermediate the guide bars 4 and 5 and extending substantially the full length of the guide channel.

In the longitudinally extending recess 14 may be accommodated the feed mechanism through which the necessary feed pressure is applied to the stack of bobby pins through the follower block. This mechanism may be in the form of a coil spring or other resilient means 15 and may apply the necessary pressure either through compression or tension, the latter being shown for this embodiment in the accompanying drawings. For the illustrated form of resilient driving means one end of the coil spring 15 is attached to the underside of the follower 9, and the other end to the base adjacent the feed end thereof, the spring intermediate its ends being looped over a pulley or like member 16 mounted in the recess 14 adjacent its outer end. For holding the follower in retracted or inoperative position, as

when the dispenser is being loaded, there is preferably provided a Z-shaped resilient latch or catch 17 mounted in the recess and having an opening or seat 17a adapted to engage and interlock with an abutment 18 on the follower when the follower is retracted.

At its upper or discharge end the guideway 3 terminates in a dispensing slot or track 19, the latter being disposed transversely or laterally of the guideway 3 and parallel to the longitudinal axes of the bobby pins in the stack. This slot is of sufficient width to accommodate but a single bobby pin and opens at one end exteriorly of the case, its side opposite the guideway being defined by a coterminous side wall 19a. Slidably mounted in the track and reciprocable relative thereto is an ejector, slide or plunger 20 through which a pin, forced or driven into the slot by the follower 9, is ejected endwise from the case transversely of the guideway and parallel to the remaining pins in the stack. To prevent jamming through intrusion of the next or adjoining pin into the slot while one pin is being ejected, the ejector 20 is provided with a rearwardly projecting extension 21 which is adapted to overlie and engage the confronting side of the next pin and particularly the closed end thereof, as the plunger moves transversely across the case, thus to ensure that the slot is occupied by but a single pin at any given time. Displacement of this next pin transversely of the stack during ejection is prevented or stopped by the upper end of the guide bar 5 which, as shown, extends to and terminates at the ejector slot.

To facilitate its operation the plunger may be provided with an offset ribbed operating knob 22 and the underside of the offset may have a depending slide, tongue or flange 23 adapted to ride in a slot or track 24 formed in or attached to the end portion of the case beyond and parallel to the ejection track 19, the tongue serving to maintain the plunger in the ejection slot during its passage across the open side of the slot connecting the latter with the guide channel 3. While undercutting the side walls of the track 24 or the ejection track 19 and correspondingly forming the interfitting parts of the plunger, the latter may be locked in its track, for illustration the plunger has been given merely a sliding fit with the case.

It is of particular importance that the bobby pins, as individually ejected from the case through the coaction of the follower 9 and plunger 20, have their open ends spread apart or open to avoid imposing this tedious and often harmful task upon the individual operating the dispenser. The device of the present invention is especially adapted to accomplish this end. This is obtained by the provision of a wedge, spacer or separator 25 interrupting or overlying the ejection slot 19 adjacent the open end thereof and having its apex or leading edge directed towards and disposed to enter the open end of the pin. As with certain of the other members, previously described, the wedge may be formed integrally with or secured to the case, that illustrated being attached to the case through an integral supporting block 26. Employing the wedge, the legs of a bobby pin are progressively separated as the pin is ejected from the dispenser, presenting the pins for use in opened condition. To enable a pin to be withdrawn from the dispenser, despite the obstacle presented by the wedge to the pin's closed or trailing end, the ejection slot, adjacent its open end 70 in the proximity or area of the wedge, is widened

or offset by cutting back the guide bar 5 to provide a passage or offset 27 clear of the wedge into which the closed end of the pin can be moved by lateral displacement relative to its path of travel through the slot, thereby enabling the pin to be free from or cleared of the wedge and removed from the dispenser.

Since threaded through the closed ends of the pins the hold-down finger 6 must terminate at or short of the ejection slot 19. While by recessing its leading edge to conform to that of the closed end of the pin the ejector can be employed to perform the function of the hold-down finger on the pin being ejected, in practice it has been found necessary only to hold the pin against vertical dislodgement from the ejection slot in the region of or adjacent the wedge. In the illustrated embodiment the desired restraint against dislodgement is obtained by a projection or extension 28 formed integrally with and projecting from the upper end of the hold-down plate and partly overlying the ejection slot in advance of the wedge. So disposed, the projection acts as a fulcrum by which the spreading action of the wedge on the open end of the pin is transmitted to maintain or hold the pin's closed end in the ejection slot.

In loading the dispenser the follower block 9 is locked in inoperative position through engagement with the catch 17. If, as in the illustrated embodiment, the finger 6 and hold-down plate 7 are attached to the base rather than being formed as a part of a cover or lid, both are removed. The bobby pins are then successively fed onto the finger by threading or piercing their closed ends thereby until a stack of the desired size has been obtained. The finger is next reinserted in the case and the hold-down plate 7 replaced forcing the open ends of the pins down against the base of the guideway and with the finger maintaining the pins in laterally aligned position, avoiding any possibility of jamming in the stack. On subsequent release of the follower block 9 the dispenser is ready to eject or dispense bobby pins individually or one by one, as desired, open end first, with separated ends and for immediate use.

Considering now Figures 7 through 13, the embodiment of the bobby pin dispenser of the present invention there illustrated, while operating in somewhat the same manner as the first embodiment, differs therefrom in certain details. Like the first embodiment, the second is comprised of a base or case 1 for housing a stack of bobby pins 2 in a longitudinally extending guideway or channel 3, and having parallelly disposed side or guide bars 4 and 5 defining or delimiting the channel. It also has a guide member or hold-down finger 6 disposed inwardly of and substantially parallel to the guide bar 4, on which the closed ends of the bobby pins are received or threaded. Additionally, there is the same longitudinal recess 14 disposed intermediate the guide bar 5 and finger 6 and below the bed 11 of the channel 3. Unlike the first embodiment, these several members, with the exception of the finger 6, have been illustrated as integral with or part of the base 1, the latter thus being formable in one piece by die casting or like means.

In place of the hold-down plate 7 of the first embodiment there is here provided a hold-down plate 29 overlying the guide bar 5 and hingedly attached adjacent the corresponding outer edge of the case. This hinged plate is normally held in flat or flush position against the guide bar 5 by a spring or like means 30. As shown, the

hinged plate partly overlaps or overlies the channel 3 and has a depending or downturned lip 31 at its inner edge which is adapted to resiliently engage and hold in place the open ends of the stacked bobby pins.

For urging the pins 2 toward the upper or discharge end of the case there is provided a follower or pressure block or bar 32 which is adapted to act or bear against the lower or inner side of the stack of pins. This follower is of somewhat T-shape with its cross member 33 riding in the channel 3 in position to engage the side of the lowermost pin of the stack and its depending leg 34 projecting into and slidably along the longitudinal recess 14, the leg-confronting side walls of the recess serving to maintain the follower in its position transversely of the case.

For aiding in guiding the follower, as well as holding it in the case, here is provided a U-shaped guide rod or member 35 disposed longitudinally of the recess and having its open end anchored at the upper end thereof. As shown, the guide rod 35 is offset transversely of the recess 14 with one or the middle arm 36 disposed substantially centrally along the longitudinal axis of the recess and the other side or inner arm 37 disposed adjacent one side of the recess. For engagement with the guide rod 35 the follower 32 is pierced transversely by two holes or passages 38, one registering with and slidably receiving each of the arms. For resiliently urging the follower toward the outlet or discharge end of the case there is provided resilient means which may be in the form of a coil spring 39 wound around the guide rod. In order that its force may be applied substantially centrally of the follower, the spring is looped around the guide rod with its end encircling the middle arm 36 abutting the outer face of the follower, and its other end encircling the inner arm 37 abutting the upper end of the recess, the passage 38 receiving the inner arm 37 being enlarged sufficiently to encompass the spring. While slidably receiving the middle arm 36 the other passage is sufficiently large to permit angling movement of the follower relative thereto to enable the follower to adjust itself to corresponding movement of the stack 2.

It has been previously pointed out that the hold-down plate 29 in this embodiment is hingedly attached to the case. So constructed, the plate may be lifted when the dispenser is to be loaded so as to permit insertion of the open ends of the bobby pins thereunder. To render this action automatic there is provided on the follower an actuating pin or projection 40, projecting from the edge thereof confronting the guide bar 5, and adapted normally to ride in the space below the lip 31 of the plate occupied by the open ends of the pins. By downwardly beveling or downslanting the lip adjacent the infeed end of the case, there is provided a cam surface 41 through which the projection 40 is enabled to progressively lift or raise the hinged plate as the follower is withdrawn against the force of the spring 30 preliminary to loading, the consequent cam action raising the lip sufficiently to permit insertion of the open ends of the pins thereunder.

At its upper or discharge end the guide channel 3 terminates in or is delimited by a dispensing or ejecting slot or track 42 which is disposed transversely or laterally of the guideway 3 and parallel to the longitudinal axes of the bobby pins in the stack, the slot being defined on its

side opposite the guide channel by a coterminous side wall 42a. As in the case of the first embodiment, this track is sufficiently wide to accommodate but a single bobby pin and opens exteriorly of the case 1 at its end corresponding to the open ends of the pins. Unlike the track of the first embodiment, the bottom wall or pin-supporting surface 43 of the present track is upwardly inclined or upslanting adjacent its ejection or open end, this upslant acting on the lower leg of the bobby pin to progressively tilt or cant the latter as it moves along the track. Overlying the upslanting portion 44 of the track is a wedge or spreader 45 which is disposed in the path of and adapted to enter and progressively spread the open end of a bobby pin as the latter moves towards the ejection end of the track.

It will be noted that the hinged hold-down plate 29 of this embodiment does not project into the projection slot and thus cannot assist in holding the pin within the track as the latter is ejected, this modification being necessary because of the tilting of the pin. However, the same result is accomplished here by the spreading action, the greater dislodgement of the upper end of the pin, as it is spread, applying a force sufficient to hold the closed end of the pin within and against the undersurface of the track. Once a pin has been spread to the extent desired it is removed from the dispenser in the same manner as the first embodiment through the provision of an offset 46 in the slot adjacent the spreader for receiving and freeing or releasing the closed end of the pin.

The above described ejection of each bobby pin as it enters the ejection track is obtained through a plunger or ejector 47 having an offset ribbed operating knob 48. In the first embodiment a tail or extension 21 is utilized for holding the next pin out of the slot while one is being ejected. Here the same result is obtained by providing on the ejector a beveled flange 49 which projects beyond the ejection track and is adapted to override the next pin. By preventing the next pin from jumping out of the guideway and forcing the side of the pin to bear against the confronting side of the ejector during reciprocation of the latter, the flange 49 inhibits the next pin from entering fully into the ejection slot until the ejector is returned to its initial position. For attaching the ejector to the case, the latter is preferably transversely slotted adjacent its upper end beyond the ejection track to receive a U-sectioned slide 50, the sides of which are spaced from confronting walls of the case. This slide or track may be attached to the case by screws or like means and is adapted to slidably engage and interlock with the ejector 47 through the provision of a pair of depending legs 51 on the latter embracing or engaging the sides of the slide and each having inturned flanges 52 at their lower ends for locking the ejector against displacement.

In operation, the second embodiment of the dispenser is loaded in the aforementioned manner by withdrawing the follower 32 toward the feed end of the case, this same movement lifting the hinged plate 29. If desired, the follower may be held in withdrawn position by a catch or like means (not shown), such as that provided for the first embodiment. After the stack of pins has been loaded on the finger 6 in the manner previously explained, the dispenser will successively eject individual pins merely by operation of the ejector through its operating knob, each

pin being tilted longitudinally in process of ejection and thus presenting its spread open end in easily accessible lip-tilted position, ready for use.

It has been previously mentioned that the follower has sufficient clearance relative to its U-shaped guide rod to allow relative angling movement of the former. As the reciprocable plunger is withdrawn for recocking after a pin is ejected, first the open end and ultimately the closed end of the next pin is exposed and free to enter the ejection slot. The follower being capable of limited angling movement and having pressure applied approximately at its center, will thus cause the stack to angle as the slot is exposed, thereby progressively feeding the next pin into the slot.

From the above detailed description it will be apparent that there has been provided an improved bobby pin dispenser capable of dispensing pins individually as desired and in open condition ready for use, the dispenser also being particularly adapted to prevent jamming of the pins during their progress therethrough. It should be understood that the described and disclosed embodiments are merely exemplary of the invention and that all modifications are intended to be included which do not depart either from the spirit of the invention or the scope of the appended claims.

Having described my invention, I claim:

1. A bobby pin dispenser comprising a case adapted to receive a stack of bobby pins, guide means in said case for maintaining said pins in lateral alignment, a resiliently urged follower 30 associated with said guide means for forcing said pins toward one end of said case, an ejection track in said case disposed in the path of and adapted to receive one of said pins, said track having a coterminous side wall opposing said follower, means for ejecting said one pin from a side of said case along said track, and means adjacent the ejection end of said track for entering an open end of and spreading said pin during ejection thereof.
2. A bobby pin dispenser comprising a case adapted to receive a stack of bobby pins, a guideway in said case for maintaining said pins in lateral alignment, means associated with said guideway for resiliently urging said stack toward an end of said case, a wall delimiting the end of said guideway and opposing said urging means, said delimiting wall including said end and extending therebeyond to a side of said case, means reciprocable transversely of said guideway for ejecting one of said pins from said side of said case, and means disposed in the path of and engageable with an open end of said one pin for spreading said pin during ejection thereof.
3. A bobby pin dispenser comprising a case adapted to receive a stack of bobby pins, a guideway in said case for maintaining the pins in said stack in aligned relation, resilient means for normally urging said stack along said guideway, means disposed transversely of said guideway for receiving one of said pins, said pin-receiving means having a coterminous side wall opposing said urging means, means reciprocable along said transverse means for ejecting said pin from a side of said case, and a spreader disposed in the path of an open end of said pin for spreading said pin during ejection thereof.
4. A bobby pin dispenser comprising a case adapted to receive a stack of bobby pins, a guideway in said case for maintaining the pins in said stack in aligned relation, resilient means for nor-

mally urging said stack along said guideway, an open-ended ejection slot disposed transversely of and delimiting said guideway for receiving one pin of said stack, said slot having a coterminous side wall opposing said urging means, an ejector reciprocal along said slot for ejecting said pin from a side of said case open end first, said ejector abutting a side of and preventing entrance of the next pin in said stack into said slot during said ejection, and a spreader interrupting said slot adjacent the open end thereof and positioned to engage the open end of and spread said pin during ejection thereof.

5. A bobby pin dispenser comprising a case adapted to receive a stack of bobby pins, a guideway in said case for maintaining the pins in said stack in lateral alignment, means for resiliently urging said stack toward an end of said case, an ejection slot extending transversely of said guideway to a side of said case and delimiting said guideway for receiving one of said pins, said slot having a coterminous side wall opposing said urging means, an ejector reciprocal of said slot for ejecting said pins from said side of said case open end first, a spreader interrupting said slot adjacent an end thereof and lying in the path of said open end for spreading said pin during ejection thereof, and means partly overlying said slot for holding said pin in said slot during said ejection.

6. A bobby pin dispenser comprising a case adapted to receive a stack of bobby pins, a guideway in said case for maintaining the pins in said stack in lateral alignment, means associated with said guideway for resiliently urging said stack toward an end of said case, an ejection slot extending transversely of said guideway to a side of said case and delimiting said guideway for receiving one of said pins, said slot having a coterminous side wall opposing said urging means, an ejector reciprocal of said slot for ejecting said pin from said side of said case open end first, a spreader interrupting said slot adjacent an end thereof and lying in the path of said open end for spreading said pin during ejection thereof, means associated with said guideway and partly overlying said slot for holding said pin in said slot during said ejection, and said case having an opening connected to and offset from said slot beyond said holding means permitting transverse displacement and disengagement of said spread pin from said slot and removal from said case.

7. A bobby pin dispenser comprising a case adapted to receive a stack of bobby pins, a guideway in said case for maintaining the pins in said stack in lateral alignment, means associated with said guideway for resiliently urging said stack toward an end of said case, an ejection slot extending transversely of said guideway to a side of said case and delimiting said guideway for receiving one of said pins, said slot having a coterminous side wall opposing said urging means, an ejector reciprocal of said slot for ejecting said pin from said side of said case open end first, a spreader interrupting said slot adjacent an end thereof and lying in the path of said open end for spreading said pin during ejection thereof, and means associated with said guideway and partly overlying said slot for holding said pin in said slot during said ejection, said means cooperating with said spreader to maintain the closed end of said pin in said slot.

8. A bobby pin dispenser comprising a case adapted to receive a stack of bobby pins, a guideway in said case for maintaining the pins in said

stack in aligned relation, means for urging said stack toward an end of said case, an ejection slot extending transversely of and delimiting said guideway for receiving one of said pins, said slot having a coterminous side wall opposing said urging means, an ejector reciprocal of said slot for ejecting said pin from a side of said case open end first, a spreader contained within and interrupting said slot adjacent an end thereof, said spreader lying in the path of said open end for spreading said pin during ejection thereof, and said case having an opening in said side adjacent said spreader and offset inwardly of said end wall permitting displacement of the closed end of said pin thereinto and removal of said pin from said case.

9. A bobby pin dispenser comprising a case, a guideway within said case for housing a plurality of bobby pins, means for successively ejecting individual pins from a side of said case, and wedging means spaced offset from and having its leading edge disposed parallel to said guideway for entering an open end of and spreading each of said pins during ejection thereof.

20 10. A bobby pin dispenser comprising a case, means in said case for housing a plurality of bobby pins, an ejection track adjacent one end of said case for receiving an individual pin, means reciprocal of said track for ejecting said pin therethrough from said case, and means associated with said track for entering and spreading the open end of said pin during ejection thereof, said track having an outlet including said spreading means and offset therefrom toward the opposite end of said case for removing said pin from said case.

25 11. A bobby pin dispenser comprising a case, means in said case for housing a plurality of bobby pins, an ejection track extending through a side of said case for receiving an individual pin, reciprocal means for ejecting said pin through said track from said side of said case, and means associated with said track for both tilting said pin about a closed end thereof and spreading said pin during ejection thereof.

30 12. A bobby pin dispenser comprising a case, means in said case for housing a plurality of bobby pins, an ejection track inclined adjacent its outer end, means for ejecting a pin from said case through said track, and a spreader overlying said incline, said ejecting means cooperating with said spreader and incline for spreading and tilting said pin during ejection thereof.

35 13. A bobby pin dispenser comprising a case, a guideway in said case for receiving a stack of bobby pins, a finger insertable through closed ends of the pins of said stack for maintaining said ends in said guideway, a guide plate hingedly attached to said case and overlying open ends of said pins for maintaining said ends within said guideway, a follower for resiliently urging said stack along said guideway, means associated with said follower and engageable with a cam face on said plate for lifting said plate to permit insertion of said open ends thereunder, an ejection track disposed transversely of said guideway for successively receiving an individual pin from said stack, an ejector reciprocal of said track for ejecting said individual pins therethrough from said case, said track having an incline adjacent its ejection end, and a spreader overlying said incline, said ejector cooperating with said incline and spreader for tilting and spreading an open end of said pin during ejection thereof.

40 14. A bobby pin dispenser comprising a case, a

11

guideway in said case for receiving a stack of bobby pins, means adjacent a side of said guideway for receiving open ends of said pins, a resiliently urged follower for resiliently urging said stack along said guideway, an ejection slot associated with said guideway for successively receiving an individual pin from said stack, said slot having a side wall substantially coterminous therewith and opposing said follower for engaging and guiding said pin, means for ejecting said pin from a side of said case along said slot, and means for entering an open end of and spreading each of said pins during ejection thereof.
